UNITED STATES PATENT OFFICE.

WALTER S. BIXLER, OF CONNELLSVILLE, PENNSYLVANIA.

DESIGN FOR A COAT BADGE OR SIMILAR ARTICLE.

Application filed August 22, 1927. Serial No. 23,181. Term of patent 7 years.

To all whom it may concern:

Be it known that I, WALTER S. BIXLER, a citizen of the United States, residing at Connellsville, in the county of Fayette and State of Pennsylvania, have invented a new, original, and ornamental Design for a Coat Badge or Similar Article, of which the following is a specification, reference being had to the accompanying drawing, forming part thereof.

The figure is a perspective view of the article, showing my new design.

I claim:—

The ornamental design for a coat badge or similar article as shown.

WALTER S. BIXLER.
